3 Claims. (Cl. 200—67)

This invention relates to an electrical snap-action switch, in particular for electrically heated apparatus such as continuous-flow heaters. Snap-action switches are well known in various modifications, wherein a shift lever can be moved through its dead center position and is connected with a contact arm by means of a snap-action spring. In such switches, the snap-action spring changes its direction of operation and suddenly moves the contact arm into its make or break direction, as soon as the shift lever passes through its dead center position. In many cases, in particular in power switches for electrically heated apparatus, the shift lever must be actuated non-positively by a moving member such as the push rod of a diaphragm exposed to water pressure or by the expansion member of a thermostat. If such a moving member makes a slow movement and this is the case as a rule, the shift lever is approached to its dead center slowly. As a consequence, the contact pressure depending on the snap-action spring is decreased during the switching-off operation and reaches the value of zero in the dead center position before the contact arm is lifted from the counter-contact by the snap-action spring after the dead center position has been passed through. This means that with such a snap-action switch, an uncertain contact tending to freezing together is obtained in the neighborhood of the dead center, if the shift lever is actuated non-positively by a slowly moved member.

The invention has for its object to maintain the full contact pressure in such a snap-action switch up to the moment of breaking, even with slow actuation of the shift lever.

According to the invention this is achieved in that the shift lever is blocked by a locking device in the make position of the contact arm, and that the locking device can be released by the moving member lifting from the blocked contact arm, when this member moves past a position corresponding to the dead center of the shift lever. Thus the shift lever is prevented by the locking device from following the slow moving member during the switching-off movement, and is released only in that moment when the moving member has already moved backwards to such an extent that a sudden breaking is effected. In principle, such an arrangement comprising a locking device for maintaining the full contact pressure can be employed in all possible embodiments of such dead center switches. The additional expenses required are extremely small. Advantageously the locking device comprises a spring loaded pawl, which can be released by a cam provided on the moving member.

An embodiment of the invention is shown more or less schematically, in the accompanying drawing.

A shift lever 1 designed as a flexible blade and a contact arm 2 also designed as a flexible blade of an integral stamping is fixed at 3 to the switch casing (not shown). A compression spring 4 is fixed between the free end of the shift lever 1 and the contact arm 2. A push rod 6 acts on the shift lever 1 against the action of a return spring 5. A spring loaded locking pawl 7 is pivotally mounted in the switch casing. Pawl 7 blocks the shift lever in the position shown. The locking pawl can be released at a certain position of the push rod 6 by means of a cam 8 provided on the push rod. Reference numeral 9 designates a stop for the contact arm

2. The stationary counter contact 10 cooperates with a contact 2' of the contact arm 2 to close the electric circuit.

In the embodiment shown the switch is actuated by 5 the water deficiency safety device of an electrically heated continuous-flow heater. It will, of course, be understood that the invention is not limited to such or similar applications.

The continuous-flow heater comprises a main body 11 provided with a U-shaped heating channel 12. A heating coil 13 is arranged in the heating channel 12. This coil is supplied with current from an A.C. current source 14 through the contacts 2', 10 of the switch described. Channels 15 and 16 are provided in series with the heating channel 12 at the inlet and at the outlet side thereof. The heating coil is not insulated and arranged in the water flow, and the water columns in the channels 15 and 16 constitute electric resistors which limit the leakage currents and make it possible to ground the inlet and the outlet of the apparatus. This principle of an electric continuous-flow heater is well known per se and forms no part of the present invention. A throttle screw 17 is provided between channels 15 and 12.

A bell-shaped diaphragm casing 18 is placed on the main body 11. The main body 11 is provided with a recess 19 on its top face. The recess is connected with the channel 15 through a bore 20. A diaphragm 21 is clamped between the main body 11 and the diaphragm casing 18. The space 22 above the diaphragm 21 is connected to the channel 16 through a channel 23 passing through the outer rim of the diaphragm 21.

The push rod 6 is passed through the diaphragm casing 16 by means of a stuffing box 24, and, at its lower end, carries a diaphragm plate 25 which comes into contact with the diaphragm 21 under the influence of a spring 26, if the diaphragm makes a stroke. The push rod 6 is provided with a shoulder stop 27 and is enclosed by the fork-shaped end of a leaf spring 28 which rests on the shoulder 27 and is fixed at 29. A screw 30 presses on the spring 28. By means of screw 30 the spring 28 may be more or less pre-tensioned.

The switch stop 9 is conducting part of the circuit and is connected with the contact 2' by a flexible conductor 31.

45 The device described operates as follows:

If the tap valve (not shown) is opened, a dynamic pressure drop at the throttle 17 is obtained in well known manner, which becomes effective on the diaphragm in the spaces 19 and 22 through channels 29 and 23, respectively. The diaphragm makes a stroke and lifts the push rod 6 against the action of the springs 26 and 28. By adjustment of the screw 30 the pressure to which the device responds can be varied in order to permit an accommodation to the local conditions. Upon closure of the tap valve the pressure drop is decreased and the push rod 6 is moved downwards under the influence of the springs 26 and 28.

In the make position shown of the contact arm, a sufficient contact pressure between the contacts 2, 10 is produced by the compression spring 4. The push rod 6 non-positively abutting the shift lever 1 has lifted the lever 1 to such an extent that the locking pawl 7 has snapped in and blocks lever 1.

60 When the push-rod 6 has moved downwards the switch 65 is to break. With initial movement, the push-rod 6 moves down away from the blocked shift lever 1. Only after a predetermined movement of the push rod 6, the locking pawl 7 is released by means of cam 8. The shift lever 1 is moved downwards under the influence of the return spring 5 and passes through its dead center in the plane of the contact spring 2. During this operation, the compression spring changes its direction of operation

and lifts the contact spring 2 from its counter contact 10 so that it abuts the stop 9. It is essential that the release of the pawl 7 is effected only when the push rod 6 has passed through a position corresponding to the dead center position of the shift lever 1. By the blocking of the shift lever 1, the full contact pressure is maintained up to the moment of breaking. The return spring 5 can be omitted, if the shift lever 1 has sufficient inherent elasticity.

Invention is claimed as follows:

1. In an electrical snap-action switch having a contact arm movable between switch-on and switch-off positions, a shift lever operatively connected to the contact arm and movable across a center position for over-the-center actuation of the contact arm, a moving member contacting the shift lever for positive action to the switch-on position and movable between switch-on and switch-off positions through a point corresponding to the center position of the shift lever, and means urging the shift lever towards the switch-off position, the improvement comprising: a releasable latch engaging the shift lever in the switch-on position; and actuating means connected to the moving member to release the latch after the moving member has moved from the switch-on position to beyond said point.

2. In a switch as set forth in claim 1, wherein said latch comprises a pivotally mounted pawl movable between a latched and an unlatched position and having a portion blocking the shift lever in the switch-on position, and means connected to the pawl and urging the pawl to said latched position; and said actuating means comprises a cam connected to the moving member and contacting said latch when in the latched position to move the latch to the unlatched position.

5 3. An electrical snap-action switch including: a flexible contact arm having a supported and an unsupported end; a flexible shift lever having a supported and an unsupported end and having its supported end integral with the supported end of the contact arm; means fixedly 10 mounting the supported end of each of the arm and the lever with the unsupported ends extending in a common direction; resilient means interconnecting unsupported portions of the lever and arm, whereby as the lever is moved across center from one side to the other side, the arm will move from a switch-on to a switch-off position and vice versa; a contact contacting the arm when the arm is in the switch-on position; means operatively connected to the lever to urge the lever from said one side towards the other; an operating member positioned at the other side of the lever, said operating member being movable toward said one side to contact and move the lever to said one side against said urging and to retract beyond the center; a pivoted latch engaging 15 the lever when the lever is at said one side; and a cam attached to the operating member to contact said latch and disengage it from the lever after said operating member has so moved beyond center from said one side.
